SELF-LOCKING FASTENER

Chester E. Warner, Oak Park, Ill., assignor to
 United States Gypsum Company, Chicago, Ill.,
 a corporation of Illinois

Application September 17, 1942, Serial No. 458,685

10 Claims. (Cl. 85—11)

This invention relates to fasteners for securing panels to supports, and more particularly to driving fasteners for securing asbestos shingles or the like to gypsum sheathing. Such shingles are ordinarily formed of hard pressed asbestos cement mixture, and are very tough, strong and firm in texture and capable of retaining a fastener secured thereto or therein.

The shingles are not frangible and do not easily crumble or break away from plaster. The gypsum sheathing, however, which forms a deck or support to which the shingles are to be secured, is substantially identical with ordinary plaster-board, except that it is usually somewhat thicker and may be provided with somewhat heavier fabric cover sheets.

The core of the gypsum sheathing is very frangible and will not hold a nail or the like in a satisfactory manner. It has been found in practice that when asbestos shingles are secured to a gypsum sheathing deck by means of ordinary driven fasteners, such as nails or the like, the shingles are easily loosened from the deck by the wind or other conditions, and for this reason, building structures having walls or roofs of this type have been unsatisfactory.

When nails or similar fasteners are driven through the sheathing, small amounts of the sheathing material adjacent the inner surface are apt to be broken away as the fastener is driven therethrough. This leaves an opening at the back of the sheathing which is larger than the fastener and there is, therefore, very little holding power to retain the fasteners in place.

Nails or similar fasteners after once being loosened in the gypsum sheathing cannot again be secured in place as the core of the sheathing crumbles away from the fastener. Asbestos shingles are usually very hard, and it has therefore been common practice to provide preformed holes therethrough to receive nails or similar fasteners. Such holes may be provided when desirable for use in connection with the fasteners of the present invention; however, holes are not required through the gypsum sheathing.

It is an object of the present invention to provide a self-locking fastener which may be driven through the shingles and sheathing and secured in place by resilient pressure applied at or adjacent the back of the gypsum sheathing.

A further object is to provide a fastener to be driven in the same manner as an ordinary nail, and which, when driven completely in, will expand adjacent the piercing end so as to apply a snug resilient pressure within the opening

formed by the fastener and at or adjacent the back surface of the sheathing.

A further object is to provide a driving fastener having a driving shank, and an auxiliary shank adapted to limit the driving of the piercing end, so that further driving of the shank will cause the fastener to expand adjacent the piercing end and resiliently engage the sheathing to retain the fastener snugly in place.

10 It is also an object to provide a fastener of the type described having means automatically positioned by driving the fastener completely into place to align a succeeding row of shingles.

Another object is to provide a self-locking fastener which may be made of a single piece of sheet metal if desired, and which will be cheap to manufacture, convenient in use and which will tend to take up any looseness due to the crumbling away of the material of the sheathing after 15 the assembly of the structure.

20 Further objects will be apparent from the specification and the appended claims.

In the drawings:

Fig. 1 is a perspective view of a fastener illustrating one embodiment of the invention and formed of a single piece of sheet metal.

Fig. 2 is a side elevation of the embodiment shown in Fig. 1, partly driven in place, with the shingle and sheathing shown in section.

30 Fig. 3 is similar to Fig. 2, but illustrates the fastener completely driven in place and a succeeding overlapping shingle applied to the structure.

Fig. 4 is a plan view of the blank from which 35 the embodiment shown in Figs. 1, 2 and 3 may be formed.

Fig. 5 is a detailed sectional view taken on a line substantially corresponding to line 5—5 of Fig. 2.

40 Fig. 6 illustrates a preformed opening through an asbestos shingle to receive a fastener.

Fig. 7 is a perspective sectional view taken on a line substantially corresponding to line 7—7 of Fig. 4, but illustrates a slightly different type of 45 weakened transverse lines, which lines are provided for facilitating the self-locking expansion of the fastener during the driving thereof.

Fig. 8 is a perspective view of another embodiment of the invention formed of two separate 50 pieces of sheet metal.

Fig. 9 is a longitudinal axial section through the embodiment shown in Fig. 8.

Fig. 10 is a front elevation of the driving shank shown in Figs. 8 and 9.

55 Referring to the drawings in detail, the em-

bodiment illustrated in Figs. 1 to 4, inclusive, comprises a sheet metal fastener, which may be formed from a suitable blank, such as shown in Fig. 4.

It will be apparent that the fastener may be made in various forms without departing from the spirit of the invention; however, in the present instance, the fastener illustrated comprises a central elongated driving shank or compression element 1 having a piercing end 2 and a striking end 3. The blank is sheared along lines 4 and 5 to provide tension arms or elements 6 and 7, respectively, which extend parallel with the driving shank from adjacent the piercing end of the fastener. Each arm terminates in a rearwardly extending flange, head, shoulder or anchorage means 8 having a forwardly extending portion 9, so that a portion of the flange will extend on each side of the associated arm and engage a work surface when the fastener is driven in.

The driving shank 1 extends materially beyond the ends of the arms 6 and 7 and the upper portion of this shank may be corrugated as shown at 10 or otherwise formed in any suitable manner to reinforce the projecting end portion of the shank, so that any bending which takes place when the fastener is driven will occur adjacent the piercing end.

In the embodiment illustrated, the shank 1 is provided at its striking end with a rearwardly extending arm 11 which terminates in a return hook 12 or abutment, as illustrated. This hook is of the proper size to engage over the end of an overlapping asbestos shingle or the like, as shown in Fig. 3. The sides of the shank 1 are cut away by means of perforations 13 and 14, the perforation 14 being closely adjacent the piercing end of the fastener and the perforation 13 being spaced somewhat therefrom. These perforations are for the purpose of weakening the shank along transverse spaced lines, so that when the fastener is completely driven into a support to extend therethrough as shown in Figs. 2 and 3, the fastener will automatically take the self-locking form shown in Fig. 3.

The material of the fastener is sufficiently resilient and bendable so that during the driving process, the shank will bend along the line of the perforations and assume the required self-locking form with the tension arms 6 and 7 resiliently pressed snugly against one side of the perforation formed by the fastener, and the shank will snugly and resiliently press against the opposite side of the perforation.

It will be apparent that score lines may be made along the dotted lines 13a and 14a, and, if desired, the perforations may be omitted. Also, the material of the fastener shank may be slightly indented along transverse lines 13b and 14b, as shown in Fig. 7. These perforations and score lines are not essential; however, they assist in forming the fastener in a desired self-locking relationship to the support as it is being driven therein.

Fig. 2 illustrates the fastener driven through asbestos shingles or the like 15 and the associated gypsum sheathing 16 which forms the support for the shingles. The shingles are preferably perforated as shown at 17 (Fig. 6), and this perforation is of a contour to permit the entrance of the corrugated portion 10 of the shank.

As shown in Fig. 2, the flanges 8 are in contact with the outer surface of the shingle 15 and the piercing end of the fastener has been extended completely through the gypsum sheathing 16.

In driving through this sheathing, there is a tendency for the gypsum core to break away slightly adjacent the inner surface as shown at 17, and the expansion of the inner end of the fastener, when it is completely driven in, brings the tension arms 6 and 7 and the shank 1 into snug resilient self-locking engagement with the sides of the perforation, as shown in Fig. 3.

In the partially driven position of the fastener, as shown in Fig. 2, the flanges 8 are in contact with the shingle and further driving of the shank 1 places the arms 6 and 7 under increasing tension as the shank is driven in until it is substantially flush with the outer surface of the shingle, in which position the fastener has assumed the self-locking position shown in Fig. 3. The inner end of the fastener thus forms a substantially triangular loop in which that part of the shank forming the base 18 of the triangle retains the adjacent sides of the triangle in snug resilient engagement with the gypsum board.

It will be apparent that the direction in which the shank bends at the score line is unimportant and that the triangular self-locking formation will occur if the shank bends in either direction. In fact a very satisfactory fastener may be made without the use of score lines or perforations.

When the fastener is completely driven in, the arm 11 rests flat against the surface of the shingle 15 with the hook or abutment 12 in the position shown. This provides a support and alignment for a shingle 15a of a succeeding row.

Figs. 8, 9 and 10 illustrate another embodiment of the invention, which embodiment comprises a tension shank or arm 19 having a pointed piercing end 20. This arm is provided with a rearwardly extending flange 21 having forwardly extending portions 22, and these flanges and portions function in the same manner as the flanges 8 and portions 9 on the previously described tension arms. The flange 21 terminates in a return hook 22a for engaging the lower end of a shingle in the overlapping row. The flange 21 is perforated at 23 to receive a driving shank 24, the upper end of which is preferably corrugated or channel-like in cross section, as shown. The construction of this arm is illustrated in Fig. 10, and the lower end is provided with an extension or lug 25, which lug is adapted to be inserted through a slot 26 adjacent the piercing end 20 of the tension shank 19. The driving shank 24 is preferably weakened along a transverse line 27 and the driving is accomplished by means of the shoulders 25a engaging the ends of the slot 26. In assembly, the lug 25 is inserted through the slot 26, and the overlapping tongue 25 and adjacent portions of the tension arm 19 are punched or pressed sufficiently to retain the elements snugly in assembled relation.

When the fastener is driven through the shingle and gypsum sheathing, it assumes the position shown by dotted lines in Fig. 9 so that the tension arm and the shank form the triangular loop illustrated to retain the fastener in resilient engagement in the work in the same manner as previously described.

Each of the embodiments illustrated discloses an arm terminating in a hook or abutment to align a succeeding shingle, however, it will be apparent that these elements are not essential and may be omitted if desired.

It is intended, of course, that the invention should not be limited to the specific embodiment or embodiments disclosed, or to the exact details of construction shown, as obvious modifications will occur to persons skilled in the art.

Having thus described this invention, what is claimed and desired to be secured by Letters Patent is:

1. A fastener comprising a strip of sheet metal having a piercing end and a striking end, said strip being sheared to provide a central driving shank and a pair of oppositely disposed tension arms extending from said piercing end alongside said central driving shank and terminating short of said driving end, said tension arms terminating in laterally extended flanges to limit the driving of said piercing end by engagement with a work surface, said material being sufficiently resilient to cause said arms and said shank to bend away from each other to form a loop at the back of a support when said driving shank is driven in beyond the limit determined by said flanges.

2. A fastener comprising a strip of sheet metal having a piercing end and a striking end, said strip being sheared to provide a central driving shank and a pair of oppositely disposed tension arms extending from said piercing end alongside said central driving shank and terminating short of said driving end, said tension arms terminating in laterally extended flanges to limit the driving of said piercing end by engagement with a work surface, said material being sufficiently resilient to cause said arms and said shank to bend away from each other to form a loop at the back of a support when said driving shank is driven in beyond the limit determined by said flanges, said driving shank being weakened on spaced transverse lines adjacent the intersection of said arms and shank to cause said loop to assume a triangular form with the base of said triangle substantially extending transversely of the longitudinal axis of said fastener.

3. A self-locking fastener comprising a sheet metal tension member having a piercing end and a head for engaging a work surface to limit the driving of the piercing end, said head comprising flanges extending laterally from each side of said member, one of said flanges terminating in a hook-like abutment for engaging the edge of a shingle or the like overlapping said fastener, one of said flanges having an opening therethrough closely adjacent the body of said tension member, said member having a transverse slot adjacent the piercing end, and a driving member slidably mounted in said opening and having its other end engaged in driving relation in said slot, said driving member being materially longer than said tension member.

4. A driven fastener for securing two panel-like members together including an elongated compression element to be driven through said securable members, an elongated tension element attached to said compression element adjacent its entering end and drawn by said compression element through said securable members, a piercing point secured to said elements and extending a substantial distance forwardly therefrom, said tension element being provided with anchorage means brought into engagement with the first entered securable member after the entering ends of both said compression element and said tension element have passed through said securable members, the forward portions of both the compression element and the tension element being bendable away from each other laterally in opposite directions from the axis of the hole through the securable members by impact exerted on the compression element after said bendable ends have passed through both said insertable members and said anchorage means has engaged said

securable member, said compression and tension elements being of sheet material lying in the same general plane.

5. A driven fastener for securing two panel-like members together including an elongated compression element to be driven through said securable members, an elongated tension element attached to said compression element adjacent its entering end and drawn by said compression element through said securable members, a piercing point secured to said elements and extending a substantial distance forwardly therefrom, said tension element being provided with anchorage means brought into engagement with the first entered securable member after the entering ends of both said compression element and said tension element have passed through said securable members, the forward portions of both the compression element and the tension element being bendable away from each other laterally in opposite directions from the axis of the hole through the securable members by impact exerted on the compression element after said bendable ends have passed through both said insertable members and said anchorage means has engaged said securable member, said compression and tension elements being in the same general plane and being formed of a single piece of sheet metal.

6. A driven fastener for securing two panel-like members together including an elongated compression element to be driven through said securable members, an elongated tension element attached to said compression element adjacent its entering end and drawn by said compression element through said securable members, a piercing point secured to said elements and extending a substantial distance forwardly therefrom, said tension element being provided with anchorage means brought into engagement with the first entered securable member after the entering ends of both said compression element and said tension element have passed through said securable members, the forward portions of both the compression element and the tension element being bendable away from each other laterally in opposite directions from the axis of the hole through the securable members by impact exerted on the compression element after said bendable ends have passed through both said insertable members and said anchorage means has engaged said securable member, said compression and tension elements being in the same general plane and being formed of a single piece of sheet metal and said tension element comprising two tension members extending along opposite edges of said compression element.

7. A driven fastener for securing two panel-like members together including an elongated compression element to be driven through said securable members, an elongated tension element attached to said compression element adjacent its entering end and drawn by said compression element through said securable members, said tension element being provided with anchorage means brought into engagement with the first entered securable member after the entering ends of both said compression element and said tension element have passed through said securable members, the forward portions of both the compression element and the tension element being bendable away from each other laterally in opposite directions from the axis of the hole through the securable members by impact exerted on the compression element after said bendable ends have passed through both said insertable members and said anchorage means has engaged said

securable member, said compression and tension elements being of sheet material lying in the same general plane.

8. A driven fastener for securing two panel-like members together including an elongated compression element to be driven through said securable members, an elongated tension element attached to said compression element adjacent its entering end and drawn by said compression element through said securable members, said tension element being provided with anchorage means brought into engagement with the first entered securable member after the entering ends of both said compression element and said tension element have passed through said securable members, the forward portions of both the compression element and the tension element being bendable away from each other laterally in opposite directions from the axis of the hole through the securable members by impact exerted on the compression element after said bendable ends have passed through both said insertable members and said anchorage means has engaged said securable member, said compression and tension elements being in the same general plane and being formed of a single piece of sheet metal.

9. A driven fastener for securing two panel-like members together including an elongated compression element to be driven through said securable members, an elongated tension element attached to said compression element adjacent its entering end and drawn by said compression element through said securable members, said tension element being provided with anchorage means brought into engagement with the first entered securable member after the entering ends of both said compression element and said tension element have passed through said securable members, the forward portions of both the compression element and the tension element being bendable away from each other laterally in opposite directions by impact exerted on the compres-

sion element after said bendable ends have passed through both said insertable members and said anchorage means has engaged said securable member, said compression and tension elements being in the same general plane and being formed of a single piece of sheet metal and said tension element comprising two tension members extending along opposite edges of said compression element.

10. 10. A fastening device for securing substantially flat panels to a relatively crumbly readily penetrable sheet material of limited thickness which comprises a sharp-ended penetrating compression element, a therewith associated tension element, and means for engaging the end of a flat panel; said penetrating compression and tension element being made of sheet metal and adapted to be driven through said sheet material so as to protrude for some distance beyond the reverse surface thereof; an anchorage element integral with said tension element and adapted to engage the surface of a secured panel so as to limit the further movement of said tension element; the ends of said compression and tension elements being bendable from each other laterally in opposite directions behind said sheet material upon the further driving of said compression element after the anchorage element has contacted the surface of a secured panel, whereby the panels are securely clamped to said sheet material.
